UNITED STATES PATENT OFFICE

CLAUDE L. ORR, OF COLUMBUS, OHIO, ASSIGNOR TO THE BUCKEYE STEEL CASTINGS COMPANY, OF COLUMBUS, OHIO

SIX-WHEEL-TRUCK CONSTRUCTION

Application filed August 24, 1928. Serial No. 301,863.

This invention relates to car trucks and has special reference to six-wheel trucks of the type disclosed in patent to Larsen and Johnson, No. 1,253,842, issued January 15th, 1918. 5 The object of the present invention is to provide a truck which is adapted to cars having a low and wide sill construction, and also to produce a bolster structure which will be firm and secure with a minimum number of fastening elements. One embodiment of the invention is illustrated in the accompanying drawings, and the invention resides in certain novel features which will be hereinafter fully described and particularly defined.

15 In the drawings;

Figure 1 is a plan view of a six-wheel truck having the invention embodied therein;

Figure 2 is a side elevation of the same;

Figure 3 is a transverse section on the line 20 3-3 of Fig. 1;

Figure 4 is a transverse section on the line 4-4 of Fig. 1.

The truck comprises side frames 1, two on each side, which have their inner ends connected by an equalizer bar 2, these parts being of any approved form. The equalizer bar carries a bearing for the center axle and each side frame carries a bearing for an end axle; each side frame also has an opening 3 there- 30 through to receive the end of a transverse bolster 4 which is supported in the opening upon springs in the usual manner.

The transverse bolsters 4 are provided with vertical shoulders 5 on their sides between 35 which the longitudinal bolsters 6 rest, and on top of the transverse bolsters are spaced perforated lugs 7 which mate with similar lugs 8 on the inner sides of the longitudinal bolsters adjacent the ends thereof, bolts or 40 locking pins 9 being inserted through said lugs to prevent separation of the parts. The transverse bolsters are depressed centrally to aid in accommodating a car body having a low wide sill construction, the depressed 45 formation producing an upwardly and out-

wardly inclined surface, indicated at 10, and the outer corner portion of each longitudinal bolster is correspondingly beveled, as indicated at 11, to rest thereagainst, the abutting surfaces aiding in preventing transverse 50 movement of the longitudinal bolsters. The ends of the longitudinal bolsters are formed into downturned hooks 12 which bear against the outer sides of the transverse bolsters and against the inner surfaces of the shoulders 55 so that the relation of the parts will be maintained.

The longitudinal bolsters are located parallel with the side frames, one on either side of the central longitudinal line of the truck, 60 and on the top of each said bolster on the side adjacent the wheels in an outwardly projecting shelf 13 which constitutes a support for the side bearing. On its inner side, at its center, each longitudinal bolster is provided 65 with a recess 14 to receive one end of the center bolster 15, said bolster being centrally depressed to approximate the depressed formation of the end transverse bolsters, as will be understood upon reference to Figs. 3 and 70 4. The lower surface 16 of the recess 14 provides a firm support for the center bolster while the outer wall 17 of the recess provides an abutment or stop against which the end of the center bolster may impinge whereby 75 the transverse movement of said bolster will be limited and the bolster will be firmly held in place without the use of bolts or similar fastening devices. The center bolster is suitably constructed at its center, as indicated 80 at 18, to form or carry a center bearing.

With this construction, the weight of the center bolster and the load thereon will retain the parts in position without the use of any fastening devices. The structure is well 85 adapted to car bodies having a low wide sill construction, and the entire load is transmitted to the side frames through the end transverse bolsters, providing ample space for the accommodation of the brake rigging. 90

Having fully described my invention what I claim as new and desire to secure by Letters-Patent, is:—

1. In a six-wheel truck, the combination of two transverse bolsters, two longitudinal bolsters mounted at their ends on the transverse bolsters, each longitudinal bolster having a medial recess in one side thereof forming a supporting shelf, the free ends of main bolster being carried by said shelves and extending only partially through the longitudinal bolsters.
2. In a six-wheel truck, the combination of two transverse bolsters, two longitudinal hollow bolsters mounted at their ends on the transverse bolsters and securely held in place by locking lugs; each longitudinal bolster having a recess in its inner wall, and a main bolster removably seated in the recesses.
3. In a six-wheel truck, the combination of two transverse bolsters, two longitudinal bolsters mounted at their ends on the transverse bolsters and securely locked in place, a main bolster; each longitudinal bolster having a side bearing table on its outer side adjacent to the wheels and a depression formed wholly within its inner wall for supporting the main bolster; the said main bolster having a center bearing.
4. In a six-wheel truck, the combination of truck side frames, transverse bolsters carried by the latter, two longitudinal bolsters supported at their ends on the transverse bolsters and located adjacent the sides of the truck, a main bolster; each longitudinal bolster having a side bearing table on its outer wall, the inner wall having a depression formed wholly therein which conforms to and removably supports an end of the main bolster.
5. In a six-wheel truck, the combination of side frames, end transverse bolsters having their ends supported in the side frames, longitudinal bolsters resting at their ends on the end bolsters and held against movement thereon and provided in their inner sides with central recesses formed wholly within their inner walls, and a central bolster having its ends engaged in said recesses in the longitudinal bolsters and resting free therein.
6. In a six-wheel truck, the combination of a plurality of transverse bolsters, a plurality of longitudinal bolsters mounted at their ends on the transverse bolsters, a main bolster of less length than the distance between the outer sides of the longitudinal bolsters, each longitudinal bolster having a medial recess in its inner side forming a supporting shelf, the ends of the main bolster resting on said shelves and extending only partially through the longitudinal bolsters.
7. In a six-wheel truck, the combination of side frames, end bolsters having their ends supported in the side frames, said bolsters

having vertical shoulders on their sides and having lugs on their tops, longitudinal bolsters having their ends resting on the end bolsters and formed into depending hooks bearing against the outer sides of the end bolsters and the shoulders thereon, lugs on the inner sides of the longitudinal bolsters, fasteners inserted through said lugs and the lugs on the end bolsters, and a center bolster having its ends freely engaged in and supported by the longitudinal bolsters.

In testimony whereof, I have signed this specification.

CLAUDE L. ORR.
